RADIATOR CLEANING APPARATUS

Charles B. Shanaman, Clarksburg, W. Va.

Application July 24, 1946, Serial No. 685,963

4 Claims. (Cl. 134—106)

1

This invention relates to devices for cleaning the interior of radiators, particularly radiators for automobiles.

It is an object of the invention to provide for effecting a circulation of a cleaning liquid through the radiator in a simple and improved manner without the use of a power driven pump or other power actuated means.

The apparatus includes a tank for containing a cleaning liquid, and a rack or holder for the radiator, the rack or holder being constructed so that the radiator may be conveniently assembled therewith, after which the rack with the radiator therein may be conveniently introduced into and removed from the tank.

Provision is made for heating the cleaning liquid in the tank, and in this connection it is an important object of the invention to utilize the rack or holder for circulating the heated cleaning liquid through the radiator.

It is also an object of the invention to provide for supporting the rack in an elevated position inclined to the vertical and on the top portion of the tank, so as to provide for draining the cleaning liquid from the radiator back into the tank for repeated use when the rack is so supported on the top of the tank.

With these and other objects in view the present invention consists in the combination and arrangement of parts, as will be hereinafter more fully described, illustrated in the accompanying drawings, and particularly pointed out in the appended claims, it of course being understood that changes in the form, proportion, size and minor details may be made, within the scope of the appended claims without departing from the spirit or sacrificing any of the advantages of the present invention.

In the drawings—

Figure 1 is a rear elevation of an embodiment of the present invention wherein the larger portion of the back of the tank is removed to show the combined fountain and radiator rack in elevation, a portion of the back of the rack being broken away to show an interior portion of the rack.

Figure 2 is a top view of Figure 1, the cover of the tank being removed.

Figure 3 is a perspective view of the combined radiator rack and fountain.

Figure 4 is a side view of the device, on a smaller scale, a side wall of the tank being removed and showing the radiator rack in position.

Figure 5 is a diagrammatic view showing the 55 of which, plates 18 incline downwardly to the

2

radiator rack support in a tilted position for draining cleaning fluid into the tank.

Figure 6 is an enlarged fragmentary view showing the manner of supporting the lower end 5 of the radiator rack for drainage purposes.

In the embodiment of the present invention as shown in the accompanying drawings, I designates a tank of general rectangular form provided with a horizontal partition 2 near the 10 bottom of the tank so as to define a combustion chamber between the bottom of the tank and the partition 2. The top of the tank is open and provided with any suitable removable cover 3. It is intended to use a cleansing fluid of any 15 suitable or preferred composition in the tank 1. As indicated in the plan view, Fig. 2, the cross sectional shape of the tank is rectangular and, as shown in Fig. 1, a vertical partition 4 is provided near one of the upright side walls of the 20 tank so as to provide an upright combustion flue 5 communicating at its bottom with the combustion chamber 6 through an opening 7 formed in the partition 2. A plurality of horizontal baffles 8 are provided within the flue 5 and on 25 the side wall of the tank and having their free edges adjacent the partition or wall 4 so as to direct the heated products of combustion towards the wall 4 to insure a proper and effective heating of said wall and the liquid contents of the 30 tank. Discharge openings 9 are provided in the back wall of the tank and communicating with the flue 5 near the top thereof for the discharge of products of combustion. A suitable gas burner 10 is provided within the combustion chamber 6 for providing the heat necessary for the 35 operation of the present invention.

In Figure 3 of the drawing there has been shown a rack or holder for the support of an automobile radiator during the cleaning operation. This rack or holder is constructed so as to enable the convenient placing of the radiator within the rack and for holding it therein particularly during the introduction and removal of the rack from the tank. As shown, the rack or holder comprises upright parallel side walls 11 connected at their tops by a top plate 12. A suitable back plate 13 covers the space bounded by the parts 11 and 12. Base members 15 project forwardly from the lower ends of the side members 11 and are connected across their front ends by a front wall 16. Within the space defined by the back wall 13, the base members 15 and the front wall 16 there is a centrally disposed horizontal plate 17, from the opposite edges

respective base members 15 and contact the same slightly above the bottom edges of the parts 15. An open-ended tube 19 is carried by the part 17, and the open lower end of the tube extends through the part 17. A plurality of vertical ribs 20 extend from top to bottom of the front face of the back wall 13. A bail handle 21 straddles the top of the rack or holder with its ends loosely or pivotally connected to the side walls 11.

In using the device as thus far described, a suitable amount of cleaning fluid is introduced into the tank 1 through the open top thereof. An automobile radiator shown conventionally at 22, is introduced into the rack downwardly through the open front thereof, and between the pipe 19 and the back plate 13, the ribs 20 constituting a guide during the placing of the radiator within the rack. Suitable supporting means 23, such as brackets are provided upon the front face of the back of the rack and on which the radiator is supported. The radiator is turned upside down prior to introduction into the rack so that the filling spout 24 of the radiator will be at the bottom and the hose connection elbow 25 will be at the top. The filling spout 24 is maintained open so that cleaning fluid may drain from the radiator back into the tank. Any suitable clamping means may be employed to hold the radiator against the front face of the back of the holder, such for instance as a pair of links 26 loosely connected to the front wall of the back of the holder, and shaped to extend around the edges of the radiator to the front thereof, such links being connected together as by means of a spring 27. One of the links 26 will have any suitable loose connection with the holder while the other one will have a detachable connection such as a hook and eye connection 28 with the holder for convenience in applying and removing the clamp. After the radiator has thus been positioned upon the rack or holder a flexible pipe or hose section 29 is fitted to the open top of the pipe 19 and the open bottom of the hose connection 25 of the radiator.

With the radiator associated with the rack or holder in the manner described, the bail handle 21 may be employed to lift the holder and the radiator and place it downwardly into the tank 1 through the open top thereof until the bottom of the rack engages and rests upon the horizontal wall or partition 2 of the tank, the cover of the tank put in place, and the burner 10 lighted, whereupon the liquid in the space or boiler chamber defined by the wall or partition 2 and the walls or plates 18 will become heated, and the heated liquid will rise through the pipe 19 and pass through the flexible hose connection 29 into the elbow 25 and then into the radiator where it will circulate downwardly and eventually discharge through the filling opening 24 of the radiator and thus back into the tank. The liquid which rises through the pipe 19 is replaced by liquid from the tank passing inwardly through the perforations 37 in either or both of the base members 15 located below the bottom edge of the plate 18. Continued circulation of the heated cleaning fluid will result in the removal of sludge from the interior of the radiator.

After a suitable period of time, the cover 3 is removed, and then the rack or holder is lifted by means of the bail handle 21 and placed in the inclined position indicated in Figs. 5 and 6 with the sockets or bearing members 30 provided on the back of the radiator rack or holder, engaged with a cross-bar 31 extending across

the open top portion of the tank. The bail handle 21 is then swung over and engaged with a supporting bracket 32 provided upon the exterior of the back of the tank 1 so as to support the rack or holder in a tilted position such that the liquid in the radiator will drain through the radiator filling opening 24 into the pan provided by the back wall 13, the front wall 16, the base members 15 and the plate members 18, from which the liquid will drain through the openings 33 in the back wall of the rack or holder and into the tank for repeated use.

Within the tank 1 and between one of the side walls 11 of the rack or holder and the adjacent tank wall there is an upstanding overflow pipe 34 having an inlet opening 35 near its top and provided at its lower end with an elbow 36 extending outwardly through one end wall of the tank so as to carry off any cleaning fluid which might tend to boil over through the top of the tank.

When the radiator has been submerged in the cleaning liquid in the tank 1, the heated liquid will expand the radiator and thereby crack off any incrustations thereon which will be carried off by the liquid discharging from the radiator.

From the foregoing, it will be understood that while a tank or casing is necessary for containing the cleaning liquid, and some provision must be made for heating the liquid contents of the tank, these parts may be varied widely and do not necessarily constitute part of the present invention, which latter is shown in Figure 3 of the drawings and comprises a rack or holder into which a radiator may be conveniently introduced and subsequently placed in a tank together with the rack which constitutes a holder for handling the radiator in introducing it and removing it from the tank. Furthermore the rack or carrier 30 also constitutes a fountain for initiating and maintaining a circulation of the cleaning liquid into, through and out of the radiator in what is a closed circuit in that the liquid in the tank is introduced into the radiator, discharged therefrom into the body of the liquid and then recirculated through the radiator.

The chamber, at the bottom of the rack or holder defined by the parts 15, 16, 17 and 18 and the bottom portion of the back plate 13 constitutes what will be termed a boiler in that the open bottom thereof is closed by the partition 2, of the tank, which partition constitutes the top of the combustion chamber 6. The liquid confined in such chamber is highly heated by the burner 10 and approaches if not actually reaches a boiling temperature in order that the heated liquid may rise through the heated tube 19. The combined area of the perforations 37 is less than the cross sectional area of the passage in the tube 19 in order that the latter may form a path of least resistance for the passage of the heated liquid and thus cause a circulation through the pipe 19 and connected parts into the radiator and back into the boiler chamber through the openings 37. It will thus be seen that the member illustrated in Fig. 3 is not only a rack or holder for the radiator but it also constitutes a pump or fountain for causing a circulation of the cleaning liquid through the radiator by reason of the heating of the liquid within the boiler chamber in the bottom of the rack. Provision is thus made for circulating the liquid for cleaning purposes without the employment of any extraneous means such as a power driven pump or other power driven means, and thus the device is self

contained and will operate under the heating influence of a gas burner or other suitable heating means.

Having thus described the invention, what I claim is:

1. In an apparatus of the class described, the combination with a tank having heating means, of a radiator-rack removably contained within the tank, said rack having means for supporting a radiator in an upright position thereon, said rack also carrying a boiler chamber at the bottom thereof in heating relation with the heating means of the tank, a conduit carried by and leading upwardly from the boiler chamber and provided with means for connection with the upper portion of a radiator supported upon the rack, the boiler chamber having an inlet from the tank for the passage of liquid from the tank into the chamber, and the tank and rack being provided with mutually cooperating means for supporting said rack with a radiator thereon on the top of the tank and inclined to the vertical with its bottom portion at the top of the tank, the lower portion of the rack having drainage openings for draining liquid from the rack back into the tank.

2. In an apparatus of the class described, the combination with a tank having means for heating liquid therein, of a radiator-rack removably contained within the tank, said rack having means for supporting a radiator in an upright position thereon, said rack also having a boiler chamber carried thereby at the bottom thereof in heating relation with the heating means of the tank and having an inlet from the tank, a conduit leading upwardly from the boiler chamber and provided with means for connection with a radiator supported upon the rack, and means for supporting said rack with a radiator thereon on the top of the tank and inclined to the vertical with its bottom portion at the top of the tank, said supporting means including bearing means on the back of the rack, a crossbar within the top of the tank for engagement by said bearing means, a swinging bail handle straddling the top of the rack and capable of being turned downwardly, and means on the back of the tank for engagement by the bail handle to prop the rack in its inclined liquid-discharging position.

3. A combined radiator support and circulating

unit comprising a rack for removable insertion within the tank of a radiator cleaning apparatus comprising an upright body, radiator supporting means carried by the body, a boiler chamber carried by and projecting horizontally at the front of the body and provided with an inlet for communication with the tank, an upright exit pipe carried by the boiler and rising therefrom and spaced in front of the body so as to receive a radiator between the body and the pipe, and conduit means carried by the top of the pipe for connection with the drain of a radiator supported upon the rack.

4. An apparatus for flushing motor vehicle radiators, the combination of a tank for holding flushing fluid and provided with a combustion chamber at the bottom thereof, a rack within the tank and comprising an upright back, a boiler compartment carried by and projecting forwardly from the bottom of the back and provided with an inlet for flushing fluid from the tank, said rack being removably supported on the combustion chamber with the boiler compartment in heat exchange relation therewith, a conduit rising from the top of the boiler compartment and spaced in front of the said back so as to receive a radiator between the conduit and the back, a connection carried by the top portion of the conduit for connection with the inlet of a radiator located between the back and the conduit, means on the front of the back to removably support a radiator thereon, and means carried by the back to hold a radiator against said back when supported thereon.
